UNITED STATES PATENT OFFICE.

BENJAMIN F. MIESSNER, OF SOUTH ORANGE, NEW JERSEY.

ELECTRICAL SIGNAL-AMPLIFYING SYSTEM.

Application filed July 8, 1926. Serial No. 121,174.

This invention relates generally to electrical systems employed for amplification of weak and minor currents such as signal currents in radio receiving and amplifying system or the like.

The present invention is in part a continuation of my application filed August 17, 1925, Serial Number 50,555, wherein a radio signal receiving and amplifying system is shown employing three electrode vacuum tubes for amplification of signals, and in which the filaments of the vacuum tubes are energized directly from a source of commercial alternating current, while the plate circuits thereof are energized from the same source of current but having a rectifying and filtering system interposed between said plate circuits and source of alternating current.

A radio signal system employing commercial alternating current, which is usually of 60 cycles, is highly economical when compared with storage batteries for supplying the same circuits. However, with the use of the alternating current there is produced "hum" in the translating devices which is objectionable. This "hum" is partly due to the use of alternating current employed for energizing the filaments of the vacuum tubes and also partly due to the character of current employed for energizing the plate circuits, which current is unidirectional but not entirely steady. More specifically, when employing current of the character heretofore mentioned for energizing the filament circuits and the plate circuits of vacuum tubes used in the reception and amplification of signal currents, there is produced disturbing or extraneous currents of approximately the same order of frequency as that of the source of alternating current employed for energizing the filaments. These disturbing currents being of a low frequency generally do not noticeably interfere with the transmission and amplification of signal currents of a high frequency, as for example, signal currents of radio frequency. However, when audio frequency signal currents are being transferred from one vacuum tube to another and are being amplified these disturbing currents, if not eliminated or neutralized, produce an annoying "hum" in the translating instruments.

In my co-pending application heretofore referred to and in my co-pending applica-

tion Serial Number 29,859, filed May 13, 1925, I disclosed certain methods and means whereby the disturbing currents may be reduced or eliminated; and the present invention embodies still other means for reducing or eliminating such disturbing currents. Such other means may be employed alone or in combination with one or more of the means disclosed in the applications above referred to, and by the use of the present invention it is possible to eliminate entirely any disturbing variations in the signal currents ultimately received.

The invention is illustrated in the accompanying drawing which is a diagrammatic view of a radio signal receiving and amplifying system corresponding to that shown in my co-pending application, Serial Number 50,550, having the present improvements incorporated therewith.

Referring to the drawing more particularly, VT^1 and VT^2 indicate vacuum tubes connected in the system for amplification of signal currents at radio frequency. VT^3 indicates a vacuum tube connected in the system as a detector of the amplified signal currents and VT^4 and VT^5 indicate two vacuum tubes connected for audio frequency amplification of the signal currents rectified by the tube VT^3 . The plate circuits of these tubes are energized by current derived from an alternating current rectifying and filtering system comprising a rectifier tube VT^6 , condensers C^1 and C^2 and an adjustable resistance R' . The filament of the tube VT^6 is energized from secondary S^1 of transformer PT while the rectified and filtered current for the plate circuits of tubes VT^1 , VT^2 , VT^3 , VT^4 , and VT^5 is supplied from a secondary winding S^2 of the same transformer. The primary P of transformer PT may be connected to a source of alternating current, such as usually employed for houselighting, through the means of plug LP and extension cord therewith as shown. Across the supply leads B^1 and PR of the rectified and filtered current there may be employed resistances R^2 and R^3 , and a lead B^2 may be extended from a point between these resistances to provide a relatively low potential current for the plate circuit detector tube VT^3 .

The secondary winding S^2 and leads A supply unrectified alternating current for heating the filaments of the tubes VT^1 , VT^2 , VT^3 , and VT^4 , while winding S^1 together

with the extension secondary windings S'^3 and S''^3 through the medium of leads A' supply unrectified alternating current of a higher potential to the vacuum tube VT^5 .
 5 Tube VT^5 is intended for operating a loud speaker LS and is a more powerful tube than the other amplifying tubes of the system. The filament circuit of tube VT^5 is preferably provided with a current control resistor R^5 while the remainder of the tubes
 10 may have their filaments connected directly across the respective supply leads therefor as shown.

The grids of all the vacuum tubes are connected to a common grid return GR . There also may be employed a grid biasing battery CB which may be connected to the filaments through a variable contact X associated with a resistance or potentiometer connected
 20 across the filament supply lines A .

The tube VT^1 may receive signal energy as shown. The tube VT^1 is coupled to tube VT^2 by a radio frequency transformer RF^1 . Preferably a tuning condenser VC^2 is connected across the secondary of the transformer RF^1 . The tube VT^2 is coupled to the detector tube VT^3 through the radio frequency transformer RF^2 . A tuning condenser VC^3 may be connected about the secondary of transformer RF^2 , the primary of said transformer comprising a variable inductance or variometer VL^2 , one end of which is connected to the plate of tube VT^2 and the other end connected to the primary
 30 of the output transformer AF^2 of tube VT^4 . A condenser C^3 is interposed between the grid return GR and the last-named end of the variometer VL^2 .

The tube VT^3 is coupled to tube VT^4 through the audio frequency transformer AF^1 , and it will be noted the lead B^2 and plate lead of the primary of this transformer are reversed with respect to the same connections for primary windings of the
 40 transformers RF^1 and AF^2 . The purpose of this reversal of connections for the primary winding of this transformer will later be fully explained. A high resistance R^6 may be connected across the secondary winding of transformer AF^1 . The output transformer AF^2 for the tube VT^4 has an intermediate point Y of its primary winding connected to the filtered and rectified current supply lead B^1 .

55 A jack J is provided which in conjunction with telephone plug TP and connections shown may be employed for connecting the head telephones HT about the secondary of transformer AF^2 . With the plug TP removed, the jack J in conjunction with the connections shown serves to connect the grid filament circuit of tube VT^5 about the secondary of transformer AF^2 .

60 It should be here mentioned that while the system disclosed in the drawings shows cer-

tain and preferred means and connections for energizing the filament and plate circuits of the vacuum tubes employed and certain and preferred means and connections for separately connecting the loud speaker 70 and head telephones to the system, it is to be understood that such means and connections are not entirely essential to the use and operation of the disturbing current neutralizing means or couplings disclosed.

75 As before stated the present invention relates to reducing or neutralizing the disturbing currents arising through the use of alternating current of a low frequency for energizing the filaments of the vacuum tubes employed, and also through the use of rectified and filtered alternating current for the plate circuit of said tubes. The reduction or neutralization of these disturbing currents is brought about by the coupling means between the vacuum tubes employed in the system and heretofore described.

80 Before proceeding with a description of the manner in which the disturbing currents are neutralized in a system of the character 90 described it may be well to state that these disturbing currents arise from several causes; among which are the slightly unsteady plate circuit currents resulting from the rectification and filtration of an alternating current; the varying potentials, alternately positive and negative, across the terminals of the filaments due to the alternating current supply for heating the filaments, and the variation of temperature of 95 the filaments which is in consonance with the alternating heating current, and which results in a varying electron emission by the filaments at double the frequency of the alternating currents.

100 Since the usual frequency of an available alternating current supply is 60 per second, it will be seen that the disturbing currents resulting from the conditions I have heretofore outlined are of an extremely low frequency compared to the radio frequency currents of the receiver and are rather low in frequency compared to the average signal currents present in the audio frequency portion of the system. Very little or no difficulty therefore arises in vacuum tubes VT^1 and VT^2 and their associated circuits because the radio frequency transformers which convey the currents through and beyond these tubes pass to a negligible degree only, the 110 disturbing currents. The difficulty begins in the detector tube VT^3 where the audio frequency transformer AF^1 more or less efficiently passes forward disturbing currents arising in this tube. These disturbing currents are subject to double amplification in vacuum tubes VT^4 and VT^5 . Similarly disturbing currents arising in vacuum tube VT^4 are more or less efficiently passed on to vacuum tube VT^5 and amplified. The dis- 115

turbing currents arising in the last tube VT^s are not subject to further amplification.

The manner in which the disturbing currents arising in a system of the character described are reduced or neutralized will now follow: It will be noted that I provide in the output circuit of radio frequency amplifier tube VT^2 a high frequency path through the variable inductance VL^2 forming the primary of radio frequency transformer RF^2 and condenser C^3 ; and a low frequency path through the upper part of the primary of audio frequency transformer AF^2 . The result is that high frequency currents passing through this tube continue on in the regular manner to the detector tube, while low frequency currents resulting from the disturbing conditions I have heretofore described act upon the audio frequency transformer AF^2 . The connections to the primary winding of the transformer AF^2 are such that currents which flow from the lead H^1 through the upper and lower parts of the primary winding oppose one another.

It will also be noted that leads of the primary of the transformer AF^2 are reversed, the connections to this transformer being such that variations in the plate circuit of the tube VT^s produce similar but opposite variations in the grid circuit of the tube VT^4 .

In operation the alternating heating current in the filament of tube VT^s produces disturbing variations in the plate circuit of this tube and these variations together with disturbing variations in the plate circuit of this tube which are caused by the somewhat unsteady character of potential supplied to the plate by the rectifier and filter, are carried over through the transformer AF^1 to the grid circuit of the tube VT^4 . Because of the reversed connections of the transformer AF^1 the resulting variations in the grid potential of the tube VT^4 are such as will tend to produce in the plate circuit of the tube VT^4 variations which are opposed to variations arising in the plate circuit of tube VT^s because of the alternating current in its filament and the unsteady source of plate current. If these variations in the potential of the grid of tube VT^4 completely neutralized the disturbing variations arising in tube VT^s it is obvious that no disturbing variations would be present in the lower part of the primary of transformer AF^2 . Current in the upper part of the primary of transformer AF^2 will be subject to disturbing variations arising in tube VT^s and these variations will be carried over to the secondary of transformer AF^2 and thence to the grid of tube VT^s . The connections to the upper part of transformer AF^2 are such that the effect of variations arising in tube VT^s as carried on to the grid of tube VT^s is to oppose disturbing variations arising in

tube VT^s . It will thus be seen that the disturbing variations arising in tubes VT^2 and VT^s are used to oppose disturbing variations arising in tubes VT^4 and VT^s .

In general practice it will often happen that disturbing variations arising in tube VT^s and carried over through transformer AF^2 to the grid of tube VT^4 will more than neutralize the disturbing variations arising in tube VT^4 . This is because tube VT^4 acts to amplify variations in potential of its grid. In point of practice, therefore the current in the lower part of transformer AF^2 will vary in phase with variations in potential of the grid of tube VT^4 . The effect of variations in the upper and lower parts of the primary of transformer AF^2 will be additive in respect to one another and each will serve to increase the effect of the other in causing variations in potential in the grid of tube VT^s . As the tube VT^s is a more powerful tube than tubes VT^2 and VT^4 the disturbing effects arising in tube VT^s will be correspondingly greater than those arising in tubes VT^2 and VT^4 and the increased variations in potential in the grid of tube VT^s will be required to neutralize completely the disturbing effects arising in tube VT^s . It will be seen that the upper part of the primary of transformer AF^2 is utilized to add to or subtract from the effect of lower part of transformer AF^2 so as to produce the desired reduction or neutralization of variations of potential on the grid of tube VT^s .

The potentiometer connected across the filament supply mains A and its adjustable contact X form an additional means for effecting a reduction in the hum. When the contact X is at some point of the potentiometer resistance other than the midpoint, it will be subjected to an alternating potential relative to the midpoint and relative to the midpoints of the filaments of the several tubes. With the contact X at one side of the midpoint this alternating potential will be opposite in phase to the alternating potential to which it would be subjected if connected to a point at the opposite side of the midpoint and these alternating potentials of the contact X, relative to the midpoint will increase as the point X is moved farther away from the midpoint. Inasmuch as the contact X is connected to the grids of the several tubes and these grids are therefore subjected to the alternating potential of the point X it is apparent that by adjusting the contact X along the potentiometer the alternating potential impressed on the grids may be varied both in amplitude and in phase. This alternating potential on the grid is superposed on the alternating potential applied to the grid through the coupling from the preceding tube, and by varying the amplitude and phase of this superposed potential, it

is possible to vary the amount of hum neutralizing current which is fed from one tube to the succeeding tube and in this manner reduce the hum current in the output circuit.

In those systems where an audible hum is apt to occur in the headphones HT when they are plugged in, across the secondary of transformer AF² I may if desired 10 provide a means whereby the plugging in of these headphones will serve to short circuit the upper part of the primary of transformer AF² thus eliminating from the secondary circuit of the transformer AF² disturbing 15 effects arising in tube VT².

While I have shown and described my neutralizing means for disturbing or extraneous currents in connection with a radio signal receiving and amplifying system it is to be 20 understood that my invention in its broader aspects can be utilized in other and similar systems and that I do not intend to limit my invention to use in the particular system shown.

25 I claim:

1. A signal current amplifying system having two vacuum tubes arranged for successive amplification of signaling currents which vary at audio frequency in the plate 30 circuit of each tube, a source of current supply for energizing a circuit of each of said tubes and tending to cause periodic disturbing variations in the plate circuits of said tubes, a coupling between the plate circuit 35 of one of said tubes, and the grid circuit of the other of said tubes, said coupling being so arranged that the variations produced in the grid circuit by the disturbing variations in the plate circuit which is coupled thereto, neutralize the variations in the plate 40 circuit of said other tube.

2. A multi-stage signal current amplifying system employing a three electrode radio frequency tube and a plurality of audio frequency tubes, adapted successively to amplify signaling current, a source of unsteady potential for supplying current to said tubes and tending to produce periodic current variations in the plate circuits of said tubes, 45 couplings between the grid circuit of each tube and the plate circuit of the preceding tube, one of said couplings being so arranged that the periodic variations from the plate circuit of the preceding tube are impressed 50 on the grid circuit of the succeeding tube, in such a way as to oppose variations in the plate circuit of the succeeding tube, and a coil in the plate circuit of the radio frequency tube, positioned in inductive relation to one of 55 said couplings and so related to said coupling that the periodic variations in the plate circuit of said radio frequency tube will act to decrease periodic variations in the plate 60 circuit of the last of said audio frequency 65 tubes.

3. A multi-stage signal current amplifying system employing a plurality of audio frequency tubes adapted successively to amplify signaling current, an alternating current supply circuit for heating the filaments 70 of said tubes and tending to produce periodic current variations in the plate circuits of said tubes, couplings between the grid circuit of each tube and the plate circuit of the preceding tube, one of said couplings 75 being so arranged that the periodic variations from the plate circuit of the preceding tube are impressed on the grid circuit of the succeeding tube in such a way as to oppose variations in the plate circuit of the succeeding tube, and a conducting connection between the grids of said tubes and said alternating current supply circuit, said connection being adjustable to connect with 80 points of said supply circuit of different potential.

4. A multi-stage current amplifying system employing three-electrode audio frequency vacuum tubes, the plate circuits of which are subject to disturbing current variations of similar frequency and phase, means for reversing the phase of such variations in the plate circuit of one of said tubes and applying said reversed variations to the grid circuit of a succeeding tube, whereby 90 the disturbing current variations in the plate circuit of a tube succeeding said second tube are reduced, and adjustable means for varying said reversed variations.

5. In a signal amplifying system employing vacuum tubes connected in cascade, each having a plate and grid, a source of fluctuating potential for energizing for operation a circuit of each tube so connected to cause 100 disturbing current variations of similar frequency and phase in the plate circuits of said tubes, a transformer between adjacent tubes poled for reversing the phase of such variations in the plate circuit of one of the tubes and applying the reversed variations 105 to the grid circuit of another of the tubes so as to reduce the plate current variations in said other tube, and adjustable means for varying the magnitude and phase of said reversed variations.

6. In a signal current amplifying system employing vacuum tubes connected in cascade, each having a plate and grid, a source of fluctuating potential for energizing for operation a circuit of each tube and tending 110 to cause disturbing current variations of similar frequency and phase in the plate circuits of said tubes, means for reducing 115 said disturbing variations comprising means for reversing the phase of such variations in the plate circuit of one of the tubes and applying the reversed variations to the grid circuit of another of said tubes, and means 120 for superposing on the reversed variations 125 other variations of similar frequency.

7. In a signal current amplifying system employing three electrode audio frequency vacuum tubes connected in cascade, a source of fluctuating potential for energizing for 45 operation the circuits of each tube and tending to cause disturbing current variations in the plate circuits of the tubes, and means for reducing said disturbing variations comprising means for reversing the phase of such 50 variations in the plate circuit of one of the tubes and applying the reversed variations to the grid circuit of another of said tubes, means for superposing on the reversed variations other variations of similar frequency, 55 and means for varying the phase and amplitude of said superposed variations.
8. A multistage electrical amplifying system comprising a pair of three electrode audio frequency tubes arranged for successive 20 single tube stages of amplification, means for supplying current of varying potential for energizing for operation one of the circuits of each of said tubes, said varying potential tending to cause disturbing current 25 variations in the plate circuits of said tubes, and means for reducing said plate current variations comprising an inductive coupling between said tubes, said coupling comprising primary and secondary windings so arranged and connected with the tubes that 30 variations in the plate current from one tube are reversed and the reversed variations are impressed on the grid of the other tube in such a manner as to oppose or suppress the 35 disturbing current variations in the plate circuit of said other tube.
9. In an amplifier system having a plurality of audio amplifier tubes including an output tube, audio coupling units between 40 the output circuits and input circuits of
- electrically adjacent audio tubes, and means for energizing the filaments of said tubes from a source of alternating current whereby the space current of the several tubes tends to vary in phase accord throughout 45 said system, one of the intermediate audio coupling units being so poled that by its influence on the grid of the next succeeding tube the space current of said output tube due to transferred hum energy tends to vary 50 in phase opposed to said first tube, whereby the output circuit of the last tube is substantially free of variations produced by energization from said source.
10. In an amplifier system having a plurality of audio amplifier tubes including an output tube, audio coupling units between the output circuits and input circuits of electrically adjacent audio tubes, means for energizing the filaments of said tubes from a 55 source of alternating current whereby the space current of the several tubes tends to vary in phase accord throughout said system, one of the intermediate audio coupling 60 units being so poled that by its influence on the grid of the next succeeding tube the space current of said output tube due to transferred hum energy tends to vary 65 in phase opposed to said first tube, and means for varying the amplitude of the hum energy transferred through said intermediate audio coupling unit, whereby the output circuit of the last tube is substantially free of 70 variations produced by energization from said source.

Signed at New York, in the county of New York and State of New York, this 1st day of July, A. D. 1926.

BENJAMIN F. MIESSNER.
